KARL TÜRK, OF BALTIMORE, MARYLAND, ASSIGNOR TO THE PORCELAIN ENAMEL AND MANUFACTURING COMPANY OF BALTIMORE, OF BALTIMORE, MARYLAND, A CORPORATION OF MARYLAND

GRATE OR BURNING BAR FOR ENAMELING FURNACES

Application filed March 6, 1928. Serial No. 259,475.

The invention relates to grate or burning bars for enameling furnaces and has for its objects to provide a burning bar of improved construction and which obtains material advantages in economical and prolonged service over grate bars heretofore used in the enameling industry.

Grate or burning bars now employed for use in serving porcelain or other enameling furnaces, have been constructed of cast metal of high heat resisting capacity; for example, the bars have been cast of chromel, which is an alloy of steel with nickel, but other metals and metal alloys of high resistance may be and have been employed.

The vertically projecting points with which the bars are provided, and which support the freshly enameled articles while the same are being baked in the furnace, are in nearly every instance cast integrally with the bars and are therefore constituted of the same metal or metal alloy as that from which the bars are formed. It is essential that these points be tapered to an exceedingly fine degree to avoid perceptibly marking or scoring the freshly enameled articles which are placed on the points preparatory to being baked and hardened in the heat of the furnace. It is further necessary to make these points as hard and heat resisting as possible in order to avoid breaking, cracking and undue scaling while the same are subjected to the extremely high temperatures of the enameling furnace. Such objectionable wearing away of the points results in unevenness and lack of uniformity in the vertical dimensions of the points.

When the points are worn away or broken to uneven degree the bars may no longer be used to advantage in supporting articles to be enameled. The points are ordinarily disposed along the bars and may be spaced three or four inches apart. It is obvious that the shorter points will not assist in supporting articles and there is further danger of the latter tilting and slipping off of the bars due to the inclination resulting from the presence of the shorter points. When this condition exists it is necessary to discard the bars and replace them with new ones. This en-

tails a considerable economic waste due to the fact that the body or major portions of the bars are in undamaged condition and would be available for continuous use indefinitely were it not for the described erosion and wearing away of the points. Grate bars of the character described, due to their composition of metal or metallic alloys of high heat resisting qualities, are quite expensive in the market and involve the expenditure of an initial purchase outlay of \$2.80 per pound or higher.

Various methods have been employed to decrease or obviate this economic waste which has added materially to the operation costs of enameling plants. To this end bars of wrought iron have been employed having separate points which are riveted or otherwise rigidly secured to the bars. This has proved unsatisfactory for the reason that wrought iron does not possess the tensile and load supporting strength of cast iron and is unable to satisfactorily withstand the high temperatures in the furnace. Cast metal, which is highly superior to wrought iron in this respect, is too hard to withstand the riveting process and it is impracticable if not impossible to secure separately constructed points to cast iron grate bars, because of the tendency of the latter to break during the operation. Therefore, it has been most feasible to continue the use of cast metal bars having the necessary tensile strength and with which the spaced points are integrally cast. In casting the bars it frequently occurs that pin or blow holes exist at or near the tapered extremities of the points, the existence of which defects increase the tendency of the points to crack and break off at their tips under high temperatures. Therefore, when the points become damaged, broken or worn away as described, it has been necessary to permanently discard the entire grate bar, with the resulting economic waste described.

The present invention eliminates all of the above described disadvantages and economic waste without sacrificing any of the practical advantages incident to the employment of grate bars of cast metal of high heat resisting capacity. Integral upstanding spaced

standards or pedestals are cast with the bars as in the former practice, but these upwardly projecting standards terminate short of the desired elevation of the points and are provided with enlarged extremities forming contact or bearing surfaces. Interchangeable cap or point members of high resisting steel or alloy are separately formed, either by casting or machining or both, and these caps are 10 hollow and provided with locking means cooperating with the enlarged heads of the integral projections. In this manner the caps, which are suitably pointed in the manner of the usual integral points, are freely 15 applied to and removed from the integral projections and securely and rigidly locked thereto when the bars are in use. When one or more of the caps becomes broken or damaged as in the instance of the former integral 20 points, it is only necessary to remove the same from the projection on the bar and replace it with a fresh cap or point. It will be apparent that a great economical saving is thereby effected and it is no longer necessary 25 to discard the entire grate bar when one or more of the points has become broken or scaled away to a stunted condition.

The bars may be employed indefinitely and new caps may be applied thereto when necessary to maintain the spaced points at a uniform elevation. Various methods may be employed for removably locking the caps to the projections, the methods illustrated showing merely practical examples of detachable 35 connections of this character. It will be understood that any approved separable connection may be employed in this regard without departing from the nature and scope of the invention.

If desired, the interchangeable caps may be provided with an intermediate filler or china cement or other refractory fire resisting cement. The invention contemplates, when desired, the use of a refractory cement 40 in assisting in securing the caps to the grate bar projections, but is not limited to the use of such cement.

With such objects in view, as well as other advantages which may be incident to the use 45 of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly 50 understood there are shown in the accompanying drawings means for carrying the same into practical effect, without limiting the improvements, in their useful applications, to the particular constructions which, 55 for the purpose of explanation, have been

made the subject of illustration. In the said drawings:

Fig. 1 is a side elevation of a grate bar for 70 enameling furnaces and illustrating a preferred embodiment of my invention.

Fig. 2 is a plan view of the same.

Fig. 3 is an enlarged detail view in side elevation of one of the upstanding pedestals or standards, and showing its detachable cap member or point in vertical section. 75

Fig. 4 is a transverse section on line 4—4 of Fig. 3.

Fig. 5 is a view similar to Fig. 3 showing a modification of my invention.

Fig. 6 is a similar view showing a further 80 modification.

Referring to the drawings, 1 indicates the grate or burning bar which is or may be of the usual flat rectangular shape, and which is preferably constructed of chromel or other metal or metal alloy of high heat resisting capacity. In the enameling art to which the invention appertains, two or more of the bars are employed for supporting freshly enameled ware which is to be charged into an 90 85 95 100 105 110 115 120 125 130 furnace, and thereafter the bars are utilized in the removal of the baked enameled ware from the furnace. The bars are ordinarily loosely carried by a longitudinally reciprocable fork member constituting a part of a furnace charging or serving apparatus, and during their use the bars are repeatedly subjected for long intervals to the destructive heat of the modern enameling furnace.

The grate bar may be of any desired length and is provided with a plurality of spaced upstanding supports, pedestals or standards 2 also formed of heat resisting metal or metal alloy. The standards or supports may be of any desired number, and are suitably spaced from one another along the longitudinal dimension of the bar. In the embodiment illustrated three of such pedestals or standards are shown. The members 2 are preferably formed at their lower ends with enlarged shoulder portions 3 terminating in base portions 4, the latter being securely and rigidly seated in corresponding apertures in the grate bar. This connection may be a driving fit or the members may be shrunk into position, the shoulder portions 3 insuring proper seating of the pedestal members in the bar with respect to one another. Referring to Fig. 3, each pedestal or standard is 115 120 125 130 or may be provided with an upper enlarged portion or collar member 5, which may be cast or formed integrally with the standard, and the upper extremity of the latter terminates in an enlarged head 6 of frusto-conical configuration. The lower overhanging shoulder 7 of the head is provided with a vertically extending recess or slot 8 of a depth substantially equal to the width of the lower shoulder 7 (Fig. 4). The removable cap or

point is shown at 9, and consists of a cone shaped member preferably cast or otherwise formed of a metal or metal alloy of high heat resisting capacity. In the embodiment shown in Fig. 3, the member 9 is formed with a lower hollow socket or bore 10 of tapered configuration and of sufficient diameter to receive and seat the enlarged head 6 of the support or standard 2. In order to removably secure the point in position on its standard and to guard against accidental displacement thereof, the cone shaped member 9 is formed with an inwardly projecting lug or projection 11 which may be integrally cast with or otherwise formed on the cap or point 9. In order to assemble the cap in position the same is turned so that the lug 11 registers with the recess 8 of the head to permit the latter to seat within the innermost part of the tapering socket or bore 10. The subsequent rotation of the cap on its vertical axis positions the lug 11 beneath the shoulder 7 in the manner of the well known bayonet joint, thereby guarding against accidental displacement of the cap from its pedestal.

When it is desired to replace or interchange the cap members on the pedestals or insert new caps thereon, for example if the caps have become worn or broken, the same can be readily removed by turning, to align the lug with the recess to permit substitution of a fresh point on the pedestal.

In the embodiment shown in Fig. 5 the upper end of the pedestal is of reduced diameter as shown at 12 and is designed to fit loosely but closely within a corresponding reduced bore 13 in the point. The lower portion 13^a of the bore is of increased diameter to seat upon a collar member 14 integrally formed with or otherwise rigidly secured to the pedestal 2. The collar member is cut away to provide a groove or recess 15 for the reception of the lug 11^a of the point to permit assembling and removal of the point when desired as will be readily understood.

In the embodiment shown in Fig. 6 the upper bore 13 and the corresponding reduced portion 12 of the standard is omitted and the point 9 seats directly on the enlargement or collar 15^b of the standard. As in Fig. 5 the collar is cut away at 15^b to permit the passage therethrough of the lug 11^b of the point to permit the seating and removal of the latter, at the same time guarding against accidental displacement of the point.

From the foregoing it will be apparent that I have provided a grate bar assembly for enameling furnaces which permits of ready positioning of the points on the pedestal as well as their convenient removal therefrom, at the same time guarding against accidental displacement or loss of the points during use. The economical as well as other advantages obtained by the invention have been emphasized in the specification and will be ap-

parent. By the invention the grate bars 1, which are formed of an expensive heat resisting alloy, may be used indefinitely and provision for indefinitely maintaining the efficiency of the bars and horizontal alignment of the points to support the ware in the furnace, is insured.

In the embodiment illustrated the pedestals or standards 2 are shown separately formed and rigidly secured to the bar 1. The invention contemplates however, the standards being cast integrally with the main body portion of the bar if desired.

The caps or points have been illustrated as of conical shape, but it will be evident that the same may be constructed of pyramidal or other polygonal form, it only being desirable that the members taper upwardly or otherwise terminate in a sharp point. The invention contemplates the use of caps or points of any desired cross-sectional configuration.

What is claimed is:

1. In a grate bar for enameling furnaces the combination of a pointed cap having a recess in its bottom, means on said grate bar engaging said socket and interlocking means on said cap for preventing upward movement of said cap away from said grate bar. 90
2. In a grate bar for enameling furnaces the combination of a plurality of supports on said grate bar, each of said supports having a removable cap provided with a socket adapted to engage said support, and means for preventing upward movement of said cap relative to said support. 95
3. In a grate bar for enameling furnaces, the combination of a tapered burning point having a socket in its bottom portion, and means on said grate bar engaging said socket to prevent accidental displacement of said burning point, whereby said point may be interchanged and replaced relative to said grate bar. 100
4. In a grate bar for enameling furnaces, the combination of a burning point having a socket in its lower portion, a support having an enlarged lower portion secured to said grate bar, an intermediate portion of said support having a collar, the upper portion of said support having a head engaging said socket in said burning point to prevent accidental displacement of the latter, said burning point when in position on its support having its lower end adjacent said collar on said support. 110
5. In a grate bar for enameling furnaces, the combination of a burning point having a socket in its lower portion, a support having an enlarged lower portion secured to said grate bar, an intermediate portion of said support having a collar, the upper portion of said support having a head engaging said socket in said burning point to prevent accidental displacement of the latter, said burning point when in position on its support having its lower end adjacent said collar on said support. 115
6. In a grate bar for enameling furnaces, the combination of a burning point having a socket in its lower portion, a support having an enlarged lower portion secured to said grate bar, an intermediate portion of said support having a collar, the upper portion of said support having a head engaging said socket in said burning point to prevent accidental displacement of the latter, said burning point when in position on its support having its lower end adjacent said collar on said support. 120

In testimony whereof I affix my signature.
KARL TÜRK.
